UNITED STATES PATENT OFFICE

2,588,834

WIRE-DRAWING TENSION DEVICE

William Sawers Henderson, Glasgow, Scotland

Application May 25, 1949, Serial No. 95,181
In Great Britain May 22, 1948

4 Claims. (Cl. 205—14)

1

This invention relates to a wire-drawing bench devised to ensure constancy of pull on the wire and thus to permit the wire to be drawn to any desired degree without liability to breakage or excessive strain.

A practical embodiment of the invention is illustrated in the accompanying semi-diagrammatic drawing in which 1 denotes wire being drawn, and 2 denotes a wire drawing die. 3 denotes a drum carried by a shaft 4, the wire 1 being wound several times around the drum 3 before passing to a floating jockey pulley 5 carried at one end of a rod 6 guided to move axially through bushes 7. 8 denotes tensioning weights attached to the other end of the rod 6. 9 denotes a guide pulley provided to re-direct the wire to move in a direction co-axial with the wire at the die 2. 10 denotes a second die. 11 denotes a gear box of the swinging lever type disclosed in U. S. Patent No. 1,911,156, which box is adapted to provide an infinite range of gear ratios between the maximum and the minimum limits for which the gear box is constructed. 12 denotes the driving shaft of the gear box 11 carrying a pulley 12' connected by a belt 13 to a pulley 14 on the shaft 4. 15 denotes a pulley fixed to the gear-controlling shaft 16, rotation of which shaft 16 alters the gear ratio of the gear box 11. 17 and 18 denote cables wrapping the pulley 15 in opposite directions, an end of each cable being anchored to the pulley 15 at 19. The cables 17 and 18 are conducted around guide pulleys 20 and 21, respectively, and are passed in opposite directions around a pulley 22 freely rotatable on a pin 6' fixed to the rod 6. The other ends of the cables 18 and 17 are anchored at 23 and 24, respectively, to elements 25 and 26 of a turnbuckle device. 27 denotes a hand-wheel for altering the position of the turnbuckle device with respect to the rod 6. 28 denotes a central nut for altering the spacing of the elements 25 and 26 of the turnbuckle device. 29 and 30 denote shock absorbing springs in the cables 17 and 18, respectively. 31 and 32 denote stops on the rod 6 to limit the travel of the rod 6.

In practice, the direction of drawing is from the die 2 to the die 10, the pull on the wire 1 to draw the wire through the die 2 being provided by the drum 3 which is rotated from the gear box 11. Should the speed with which the wire 1 is drawn through the die 10 depart from the desired speed, the rod 6 will move axially, causing one or other of the cables 17 and 18 to be pulled, thereby rotating the pulley 15 and the gear-controlling shaft 16 to alter the gear ratio provided by the

2

gear box 11 to increase or reduce the speed of rotation of the drum 3 and increase or reduce the speed with which the wire 1 is drawn through the die 2.

5 The effect produced by the floating jockey pulley 5 is to regulate the speed at which the wire is drawn through the die 2, thus preventing breakages resulting from failure to maintain correct the relative speeds of the wire through the dies.

10 The initial tension in the cables 17 and 18 may be adjusted by rotation of the nut 28. The floating position of the rod 6 may be adjusted by rotation of the handwheel 27 which alters the position of the turnbuckle device with respect to the rod 6 and thus determines the initial angular position of the pulley 15 and the control shaft 16.

What is claimed is:

1. A wire-drawing bench incorporating a rotatable drum around which is led the wire to be drawn, a jockey pulley embraced by the wire and located relatively to said drum in dependence on the tension in the wire, a gear box providing a range of gear ratios and having an output shaft operatively connected to said drum for effecting its rotation, a gear-controlling shaft operatively associated with gears of said box rotation of which varies the gear ratio of said gear box, a vertical rod carried by the jockey pulley and weighted to move downwards, a freely rotatable operating pulley mounted on said rod with its axis disposed transversely of said rod, a control pulley fixed to the gear-controlling shaft, two cables wrapping said operating pulley in opposite directions, one end of each of said cables being secured to said control pulley, an anchorage means to which the other end of each of said cables is fixed, both cables being led in opposite directions around said control pulley, and means for varying the initial angular position of said gear-controlling shaft.
2. A wire-drawing bench as claimed in claim 1, in which the anchorage is constituted by a turnbuckle comprising relatively movable elements.
3. A wire-drawing bench as claimed in claim 1, in which the anchorage is axially movable with respect to the vertical rod.

4. In a wire-drawing bench, the combination including a first die and a second die through which the wire to be drawn passes, a rotatable drum mounted between said dies and around which the wire being drawn is led, a jockey pulley carried on the wire being drawn between the drum and the second die, a gear box providing a range of gear ratios and having an output shaft carrying a pulley operatively connected to said

drum for effecting its rotation and the drawing of the wire through the first die, a vertical rod carried by the jockey pulley and mounted for vertical movement, said rod being weighted for downward movement of said pulley, a freely rotatable operating pulley mounted on the said rod, a gear controlling shaft having a control pulley thereon and operatively associated with the gears of said gear box rotation of which is adapted to vary the gear ratios of said gear box and the speed of said output shaft, a pair of cables each attached by one end to and extending around said control pulley in opposite directions, said cables also wrapping said operating pulley on said rod in opposite directions, and anchorage means to which the other end of each of said cables is fixed, vertical movement of said rod being adapted to actuate said cables and rotate said

control pulley to vary the speed of the output shaft.
